UNITED STATES PATENT OFFICE.

CHARLES S. HAMILTON, OF FOND DU LAC, WISCONSIN.

DISTRIBUTING GRAIN IN MILLS, &c.

Specification forming part of Letters Patent No. 43,200, dated June 21, 1864.

To all whom it may concern:

Be it known that I, CHARLES S. HAMILTON, of Fond du Lac, in the county of Fond du Lac and State of Wisconsin, have invented a new and useful Improvement in Grain Elevators and Distributers; and I do hereby declare that the following is a full and exact description thereof, reference being had to the accompanying drawings, and to the letters of reference marked thereon.

My invention consists in an improved grain elevator and distributor, with an index.

In the accompanying drawings, Figure 1 represents a top view of my invention, placed in a mill or store-house. Fig 2 is a side elevation of the same.

In the accompanying drawings, let A represents the walls or frame of a mill or store-house, and B the floors of the same. Upon the upper floor are arranged several grain-bins, denoted in Fig. 1 by the numbers 1, 2, 3, 4, 5. These bins may be varied in number and position at pleasure.

In any convenient part of the mill I arrange an endless band provided with buckets, as seen in dotted lines Fig. 2, where F represents the said band and G the buckets. This band passes around two rollers, H and I, also shown in dotted lines. One of these rollers may be set in motion by a band or other convenient means, thus carrying the buckets up on the left and down on the right in the usual manner. The buckets, filling below, carry the grain to the top of the endless band, where they become inverted, the grain being poured out in the direction indicated by the upper arrow and conducted by spouts, directing-boards, or a hopper into the spout L, through which the grain flows into the bins below. This spout L is attached to shaft M, with which it may be revolved so as to direct the

spout L to either of the grain-bins at pleasure. On the lower part of the shaft M, and revolving with the same, is an arm or index, N, which, by pointing to one of the Figs. 1, 2, 3, &c., on the stationary ring O, indicates that the spout L is so set as to conduct the grain into the corresponding bin. By means of this index and dial ring a person in the lower part of the mill can readily perceive where the grain is being deposited in the upper part of the mill.

The details of the arrangement may be somewhat varied without departing from my invention. The spouts C and D may be made adjustable if desired, and other similar spouts may be used; or the spout L may be lengthened or shortened at pleasure; or the upper and broader part of spout L may be made stationary as a hopper, having the spout L revolving under the same.

I do not broadly claim the use of an endless apron and buckets for elevating grain; but

What I do claim, and desire to secure by Letters Patent of the United States, is—

1. The use of the revolving spout L for receiving the grain as the latter is elevated and distributing the same to the different bins, substantially as set forth.

2. The combination of the chain of buckets and the revolving spout, substantially as described.

3. The arrangement and combination of the revolving spout L, the shaft M, and index N with the chain of buckets or elevating devices, substantially as described.

C. S. HAMILTON.

In presence of—

C. MCLEAN,
J. M. GILLET.
